UNITED STATES PATENT OFFICE.

HENRY HARVEY, OF CHICAGO, ILLINOIS.

LINING FOR CHIMNEYS AND OPEN FIREPLACES.

1,416,350.

Specification of Letters Patent. Patented May 16, 1922.

Application filed August 20, 1919. Serial No. 318,675.

To all whom it may concern:

Be it known that I, HENRY HARVEY, a citizen of the United States, residing at Chicago, in the county of Cook and State 5 of Illinois, have invented certain new and useful Improvements in Linings for Chimneys and Open Fireplaces, of which the following is a specification.

Figure 1, is a perspective view of the lining ready to be placed in an open fire place. Fig. 2, is a vertical transverse sectional view on line 2—2 of Fig. 1. Fig. 3, is a longitudinal sectional view on line 3—3 of Fig. 2.

The object of my invention is to provide a 15 lining for an open fire place to be fastened to a grate at its front end by any suitable means. It is constructed so as to provide a fuel space at the back of the grate to which it is fastened. In said space a draft is 20 created around the fire basket attached to the grate or to any fire made therein where andirons are used.

In the accompanying drawing, A represents the end plates constructed of fire clay 25 or other suitable material and resting on the bottom of an open fire place, B represents the lower back plate resting on the bottom of an open fire place and C represents the upper back plate resting on the lower back 30 plate B. D represents the bevelled edge of the front end of the vertical plates which fits into a groove or recess at the back of the Grate front C' and is made fast thereto by any suitable means. E represents the joint 35 formed by fitting the edges of the back plate C to the back edges of the end plates A. A. F represents the joint formed by fitting together the edges of the back plates B and C. All joints are made air tight by cement 40 or any other suitable substance. G represents a fire basket attached to an ordinary Grate front G' and placed in the fuel space formed by my lining. H represents a front plate of which there are two, one being

placed at each end of the grate front G', and 45 serving as facings therefor. Said front plates are shown fragmentally and in dotted line but may obviously be extended upward to cover the entire length of the two end plates A, at the edges of the latter. 50

The bars G' of the grate front have their ends secured to the uprights K which latter constitute the joint between the side and front bars of the grate. This arrangement secures a rigid structure, capable of resisting 55 the tendency to accidental separation of parts through the strain incident to normal use of such grates.

Having thus described my invention, what I claim as new and desire to secure by Letters Patent, is:—

In a lining for fire places the combination of a front grate, a back plate composed of two sections, placed one upon the other, on a horizontal edge line, the lower plate inclined rearwardly and upwardly to meet the horizontal lower edge of the upper plate and the latter inclined upwardly and forwardly from the line connecting it with said lower plate, two side plates each connected by a 70 rabbet joint to the back plate at its opposite ends, each of said side plates being formed with a vertical bevel edge from top to bottom, upright bars provided on their rear face with a groove fitting over the bevel 75 edge of said plate at the lower end of said plate, and having secured thereto the opposite ends of the front grate bars, vertical front plates covering the upright bars at each side of the grate, and all secured firmly 80 together substantially as shown and described.

In testimony whereof I affix my signature in the presence of two witnesses.

HENRY HARVEY.

Witnesses:

GUSTAVE RICHTER,
MICHAEL A. SHEBLESSY.
